UNITED STATES PATENT OFFICE.

HENRY JOSEPH PODLEŠÁK, OF CHICAGO, ILLINOIS.

AUTOMATIC RELEASER FOR FIRE-DOORS, FIRE-SHUTTERS, &c.

No. 872,680.

Specification of Letters Patent.

Patented Dec. 3, 1907.

Application filed July 5, 1902. Serial No. 114,405.

To all whom it may concern:

Be it known that I, HENRY JOSEPH PODLEŠÁK, a citizen of the United States, residing at Chicago, in the county of Cook, State of Illinois, have invented certain new and useful Improvements in Automatic Releasers for Fire-Doors, Fire-Shutters, &c., and do hereby declare the following to be a clear, full, and exact description of the invention, such as would enable others skilled in the art to which it appertains to make and use the same.

My invention relates to improvements in devices for holding the fire-doors and fire-shutters open, normally, and for releasing these in case of fire in the building to allow them to close and thus shut the draft opening to prevent the fire from spreading.

The device is intended to replace the fusible metal strips now usually placed on fire-doors and fire-shutters, which fusible metal strips are placed in the doorway and are supposed to melt, when the fire reaches them, and thus release the door or shutter, allowing it to close. My device will close all the fire-doors and fire-shutters before the fire reaches these and thus prevent the fire from spreading. The draft openings in a building should be closed and hermetically sealed before the flames reach and beat through them long enough to melt any metal.

To this end my invention consists in certain novel constructions, combinations, and arrangements of parts in a device of the class described as will be hereinafter more fully described and specifically pointed out in the appended claims.

Referring to the accompanying drawings, in which like numerals refer to like parts:—

40 Figure 1 is a side elevation of a door equipped with one form of the releaser. Fig. 2 is a side elevation of the releaser shown in Fig. 1, the view being full size of the device suitable for any ordinary size of fire-door or shutter. Fig. 3 is a side elevation of a door equipped with another form of releaser which is operated by fluid pressure. Fig. 4 is a side elevation of a releaser in which the reversed form of toggle lever is used, and, 45 as shown, is adapted to be operated by fluid pressure. Fig. 5 is an elevation of the pivoted or trunnioned section of the toggle lever of Fig. 4, showing the wing *w* which receives the impact of the fluid pressure, to

trip the toggle lever at releasing. Fig. 6 is 55 a diagrammatic view, showing the arrangements of thermostatic circuits, release circuits, electromagnetic switch, piping for the fluid under pressure and an electrical device for operating the valve to turn on the fluid 60 under pressure in case of a fire.

Referring to Fig. 1, numeral 1 designates a fire door adapted to travel on a horizontal track 2. The door is shown open, being held so by the releaser which is suitably situated on, and secured to the wall. A weight 3 is attached to the door, as shown, by means of a rope, of sufficient weight and height above the floor to close the door when this is released. A hook 11, is suitably attached to the door so as to engage the free end 9, of toggle section 5^a, when the door is pushed wide open. Referring now to Fig. 2 also, 21 designates a frame or base on which the various parts are mounted. The toggle lever 75 consists of two sections, 5 and 5^a. One end of the section 5 is pivoted to the base 21 at 7, and its other end is joined to section 5^a at 6. The free end of section 5^a normally rests on the stop 8. The jointed end of the section 5 is provided with a projection 17. The purposes of this projection 17 are to limit the upward movement of the joint 6, and to effect a downward movement of said joint upon the movement of the armature 14. 85 The upward movement of the joint 6, is effected by the helical spring 16, which is coiled around pivot 7, and is arrested by the adjustable stop 30 which engages with the lip of the projection 17. The stop 30 is arranged and adjusted to allow the toggle lever to take a slight "set" upward, that is, allow the center of the joint 6 to pass a little above a straight line between the center of pivot 7, and the point of contact of the hook 95 11, and the free end of section 5^a at 9. If now, the toggle lever being in the position shown by full lines, having a slight "set" upward, a pull be exerted on the free end of the toggle lever, at 9, as it would be by the door, or rather by the weight 3, through the hook 11, the joint 6 would tend to move upward, but the upward movement is arrested by the stop 30, and hence the toggle lever will remain rigid, and hence hold the hook 100 11, and the door 1. When the upward "set" of the toggle lever is only small only a very little resistance is required to hold the tog-

gle lever rigid. And, likewise it does not require much effort to bring the toggle lever to a downward set, even when the pull of the hook 11, tending to retain the upward "set", 5 is quite considerable. Now if the toggle lever is given a downward "set", the pull of the hook 11 will tend to increase this "set", and there being nothing provided nor desired to determine the magnitude of the 10 downward "set", the toggle lever will bend at its joint 6, and will assume some such position as is shown by the dotted lines, when the hook 11 will be released and the door free to close. To bring the toggle lever from 15 an upward "set" to a downward "set", or in other words, to shift or bend the toggle lever out of its rigid position, I provide an electro-magnet 12. This electro-magnet is provided with a movable pivoted armature 14, and is 20 so mounted on the base that a hook 16, which is secured to the armature 14, will engage the lip of projection 17, upon the movement of the armature, and pull or shift the toggle lever from its upward "set" or rigid 25 position, into a downward "set". Numerals 20 designate the terminals of the electro-magnet coils.

The spring 16 is provided for the purpose 30 of making the releaser self-setting. It will bring the toggle lever to its normal or rigid position as shown, as soon as the hook 11 has passed away with the door, after having been released. The toggle lever is thus always in 35 position to engage and hold the hook 11 whenever the door has been pushed wide open.

It may be remarked that an ordinary electric door bell battery is amply strong to operate a releaser of the above form, for any 40 size of fire-door.

The door 1, though shown adapted to travel on horizontal tracks, may be adapted to slide or travel on inclined tracks, or on vertical tracks or be hinged, the releaser being 45 suitably mounted and attached to obtain the above results.

Fig. 3 shows a fire-door adapted to travel on an inclined track, and a liquid pressure operated releaser mounted on the door itself. The frame or base of this form of releaser is made of strap iron and is placed in the position usually occupied by the fusible strip frame, and the door is balanced to stay 50 normally open, by means of a rope and a weight 3, as is usually done in the fusible strip arrangement. The rope terminates in a hook 11^a, which is adapted to engage with the end of arm 9^b, of a bell crank lever b as shown. This bell crank lever is pivoted 55 at c, and its arm 9^a is adapted to engage the free end 9 of the toggle section 5^a. The section 5 of the toggle lever is pivoted to the frame 21 at 7, and the joint 6 of the two sections is made to take a slight "set" by means

of the set screw 30. The section 5 is provided 65 with a vane or a wing w similar to that shown in Fig. 5 near the joint 6, and the nozzle n is adapted to direct a stream of a liquid, or air, under pressure against the wing w, for the purpose of shifting the toggle lever from 70 its rigid position or the position of its "set" as determined by the set screw 30. The pull due to the weight 3, through the rope and the hook 11^a, on the arm 9^b of lever b, tends to push the arm 9^a upwards, but 75 this upward movement is resisted by the toggle lever, when in its rigid position, as shown by full lines in Fig. 5. As long as the toggle lever remains in this rigid position the lever b cannot turn on its pivot o, and the 80 hook 11^a cannot disengage itself and hence the door will stay open being held so by the weight 3. Now if water or other liquid under pressure is admitted into the pipe p, it will issue from the nozzle n, and being 85 directed against the wing w, will carry the joint 6 from the screw 30, shifting the toggle lever out of its rigid position. The toggle lever and the bell crank lever b, will be brought into some such position as shown 90 by the dotted lines, by the pull due to the weight 3, allowing the hook 11^a to be disengaged from arm 9^b. The door will then be released from its balancing weight 3, and will be free to close by its own weight. The 95 toggle lever need not be mounted in a vertical position as shown; it may be mounted in a manner similar to that shown in Fig. 1, when the bell crank lever b would not be necessary. If so mounted the nozzle would 100 be arranged to direct the stream downward. The purpose of mounting the parts as shown in Fig. 3 is to be able to sprinkle the door and the doorway by the operating liquid. The liquid for operating this form of releaser may be automatically admitted into 105 the piping by means of an electrical device, this being operated by the use of suitable thermostatic devices, and adapted to turn the supply or admission valve to the piping, 110 as shown in Fig. 6.

Fig. 4 shows the simplest form of my releaser. It is adapted to be secured to the frame usually put on fire-doors for holding the fusible strip. The base 21 may, however, be made of any desired shape or size to suit any particular make or size of the fusible strip frame. The members or sections 5 and 5^a, when connected as, and in the position, shown by the full lines in Fig. 4, form a toggle lever of the reversed form, in its rigid or restraining position. The joint 6 is formed by the hook of the section 5^a engaging on a projection 6^a, secured to the section 5. The two sections 5 and 5^a are not permanently 120 joined together, the section 5^a being utilized to serve as the hook 11, the rope being attached directly to the section. The rigid

position of the toggle lever is determined by the screw 30, and, as shown the shifting out of this rigid position is effected by liquid pressure, but other means for this shifting 5 may be employed. Otherwise the operation is the same as has already been explained for my other forms.

In Fig. 6, the thermostatic circuits are shown by the dotted lines and the release 10 circuits by full lines, which are provided with separate batteries or other source of current. The release circuit is closed by an electro-magnetic switch 22, which in turn is operated by the thermostats. 23 designates an auxiliary circuit leading to door 15 bells, etc., for which the batteries may be used at the same time. 20^a is a release circuit leading to a door equipped with an electrically actuated releaser, such as shown 20 in Fig. 1, where connection would be made to binding posts 20. The thermostats 25, as shown, are of the open circuit type, being closed by any abnormal rise of temperature. However, any form of thermostats 25 may be used. The closing of any one of the thermostats will cause the electro-magnetic switch to close the release circuit, thus energizing the electro-magnets therein, which will in turn attract the armatures and 30 release the doors or shutters as above described. The lever L of the valve V is held in such a position, by the toggle lever R, as to hold the valve closed; but as soon as the release circuit is closed it will release lever L 35 and the weight C will pull the lever down and thus open the valve allowing the liquid which is under pressure in the supply pipe S to flow into pipes P, B, & p, which lead to fire-doors, equipped with releasers as shown 40 at top, door 1, and terminate in nozzles n which direct the stream against the wings w, for the purpose of bending the toggle levers out of the rigid position and thus releasing the doors and shutters.

45 A hand switch 31 (one or more of them) may be provided for closing the fire-doors at will from any point within or without the building. Also the release circuit may be suitably extended to alarm bells to give 50 alarm within or without the building. The batteries may be used for call bells, annunciators, etc.

I do not limit the use of this invention to fire-doors and fire-shutters, as it may be employed for automatically closing or opening 55 valves, for releasing levers or other devices, for the purpose of starting or stopping of machinery, etc. etc.

Having thus described my invention, and 60 without limiting myself to precise constructions shown, what I claim as new and desire to secure by Letters Patent is:—

1. The combination, in automatic release devices of the class described, of a toggle 65 lever consisting of two sections, arranged and

adapted to assume a rigid position, with a means for determining said rigid position of the toggle lever, a means of shifting the toggle lever out of its rigid position, and a means of connecting a movable member, to be released, with said toggle lever when this is in its rigid position, substantially as and for the purpose set forth. 70

2. In automatic release devices, the combination of a toggle lever consisting of two 75 sections, one section being pivoted to a frame and connected with the other section so that the two may assume a rigid position, a means to determine and retain said rigid position of the toggle lever, a means of engaging the 80 toggle lever with a movable member to be released, for the purpose of holding said movable member when the toggle lever is in its rigid position, with a means for shifting the toggle lever out of its rigid position, in 85 order to release said movable member, to allow the same to move, substantially as and for the purposes set forth.

3. In automatic release devices of the class described, the combination of two members 90 or sections one of which is pivoted on a suitable frame the other section being connected to a movable member and adapted to so connect with the first said section that the two sections form a toggle lever in a certain and 95 rigid position, a means for determining and retaining said rigid position of the toggle lever, a movable member to be held in some predetermined position, a means for shifting said toggle lever out of said rigid position and 100 so releasing the said movable member and allowing it to move, and a means for operating said shifting means, substantially as set forth.

4. In automatic release devices the combination, of a toggle lever adapted to assume, and to normally be, in a rigid position, with a movable member, a means of connecting said movable member with the toggle lever, whereby the said movable member may be 110 held in a predetermined position; a means for shifting the toggle lever out of its rigid position to allow the disengagement of the said means of connection from the toggle lever, and a means for operating said means for 115 shifting the toggle lever, substantially as and for the purposes set forth.

5. In automatic release devices of the class described, the combination of a toggle lever, normally held in a rigid position, a movable 120 member, a connection between said movable member and the toggle lever, with a means for shifting or bending said toggle lever out of its rigid position, an electric circuit containing a source of electric current, an electro-magnetic switch, and thermostatic devices, said thermostatic devices being arranged to cause, when the temperature in their proximity reaches a dangerous point or degree, said electro-magnetic switch to close 125 130

a second electric circuit, which contains a source of electric current and release devices, said release devices being adapted to actuate other devices, controlling the means for bending said toggle lever out of its rigid position, substantially as and for the purposes set forth.

In testimony whereof I have signed my name to this specification in the presence of two subscribing witnesses.

HENRY JOSEPH PODLEŠÁK.
